CLAIM

The ornamental design for a luminaire housing, as shown and described.

DESCRIPTION

FIG. 1 is a perspective view of a luminaire housing showing our design;

FIG. 2 is a front elevational view thereof, where the view of the rear is a mirror image of this view and, therefore, has been omitted;

FIG. 3 is a bottom plan view thereof;

FIG. 4 is an enlarged side elevational view thereof, where the opposite side elevational view is a mirror image of this view, and, therefore, has been omitted;

FIG. 5 is a side elevational view of another embodiment of the luminaire housing of our design, wherein the length of the housing has been extended; and,

FIG. 6 is a side elevational view of yet another embodiment of the luminaire housing of our design, wherein the length of the housing has been extended an even greater amount. The broken line showing of environmental structure is for illustrative purposes only and forms no part of the claimed design.
